Des. 529

Samuel F. Pratt of Boston Mass
Afigno No

Jagger, Treadwell & Perry of Albany N. Y.
Letter Patent No. 529, Dated Nov. 20th 1832

The Schedule referred to in these Letter Patent and making part of the same.

To whom it may concern

Be it known that I Samuel F. Pratt of Boston State
of Massachusetts have produced a new and original Ornamental Design for a Franklin Stove
and I do hereby declare that the annexed accompanying drawings are full and accurate delineations
of the ornamented parts, with their several ornaments, the portions of plates not represented, being sym-
metrically similar to those represented.

What I claim as my production and desire to secure by Letter Patent is
the combination, and arrangement of ornamental figures and forms represented in the accom-
panying drawings forming together an ornamental design for a Franklin Stove
